APPARATUS FOR FILLING CARTONS AND
OTHER PACKAGESCarl Wilhelm Hartmann, Lyngby, near
Copenhagen, DenmarkApplication December 22, 1930, Serial No. 504,077
In Great Britain January 22, 1930

9 Claims. (Cl. 226—96)

This invention relates to apparatus in which a number of empty cartons or packages adapted to be charged with a retailable or other commodity, for instance granular or powdered household commodities, are successively fed to and from a device for delivering predetermined quantities of material into the cartons or packages.

The object of this invention is primarily to obtain a high rate of output from a machine for the filling and delivering of the cartons or packages (hereinafter referred to as cartons), whilst allowing sufficient time for each individual operation and especially for the weighing and filling operations. A further object is to enable a machine to be built up of a number of separate units adapted to be coupled together so as to obtain any desired total rate of output without the need for increasing the speed of individual operations. When a machine is so formed of a series of units coupled together side by side, common driving shafts may be employed for the similar parts of the various units and a single timing and synchronizing mechanism may be employed thus simplifying and reducing the cost of the whole machine.

My invention will be more clearly understood by reference to the accompanying sheets of drawings, wherein:—

Fig. 1 is a diagrammatic view showing the arrangement of filling apparatus in which two cartons are filled simultaneously, and, in succession, another two are delivered simultaneously.

Fig. 2 is a view similar to Fig. 1 but showing an arrangement of filling apparatus in which the cartons are brought successively, filled and delivered.

Fig. 3 is a part sectional side elevation view of the rotatable structure for conveying the cartons successively in alignment with the filling apparatus.

Fig. 4 is a section on the line 4—4 of Fig. 3.

Fig. 5 is a section on the line 5—5 of Fig. 3.

Fig. 6 is an end elevation view of one of the carriers of the rotating structure adapted to receive a carton for filling.

Fig. 7 is a diagram illustrating an arrangement having four weighers for each filling unit.

Fig. 8 is a side elevation view showing a nearly complete machine and conveying some idea of the general assembly and necessarily containing a large number of mechanical parts most of which need not be referred to in detail.

Figs. 9 and 9A are again similarly combined views in side elevation showing the mechanical connection between the prime mover, carton

shaping mechanism and the carton filling mechanism.

Fig. 10 is a section on the plane of the line 10—10 of Fig. 9A.

Fig. 11 is a detail sectional elevation view of the rotating hopper head of the weighing mechanism, and

Fig. 12 is a detail sectional plan view of the filling stage.

Referring more particularly to Fig. 8 of the drawings, the stack of carton blanks are indicated at the right hand side by the reference numeral 1, and the carton blanks are fed successively on to a plurality of formers 4, the appropriate former 4 having its upper side in a plane tangential with a pasting roller between the stock of blanks 1 and the formers 4. The carton blank is folded and shaped about the appropriate former by suitable mechanism. The shaped cartons closed at one end only are released from the appropriate former 4 open side up on to the conveyor surface 16¹, the cartons 16 being slid along the surface 16¹ by being individually engaged by a number of fingers 30¹. The fingers 30¹ are carried by the endless belt or chain 6 and the surface 16¹ on which the shaped empty cartons are delivered is slotted longitudinally to receive these fingers as shown in Fig. 10.

The intermittent movements of the body or frame 5 carrying the formers 4 is effected by a cam 35¹ (Fig. 9), secured to a shaft 36¹ which can carry a cam 35¹ for actuating a tappet rod 37¹ of a valve forming part of the mechanism for feeding the sheets 1. The cam 35¹ is engaged by a roller 38¹ of the frame 39¹ on shaft 40¹ and connected by a link 41¹ to a toothed segment 42¹ in mesh with a gear wheel 43¹ having a clutch connection to a shaft 44¹ carrying a gear wheel 45¹ meshing with a large gear wheel 46¹ fixed to a shaft 47¹ which carries the frame 5.

The endless belt 6 is moved intermittently by stages and synchronously with it moves an oscillating frame 39¹ which is connected by a link rod 47a (Figs. 9 and 9A) to a triangular frame 48¹ oscillating on a shaft 49¹ and formed with a toothed segment 50 meshing with a gear wheel 51¹ on a shaft 52 which carries a gear wheel 51a driving a gear wheel 53 on a shaft 54 which actuates the carton filling mechanism 31 disposed beneath a hopper 32, a revolving platform indicated at 57 in Fig. 12 receiving a pair of cartons from the conveyor surface 6, carrying them beneath the filling apparatus 31 whereupon they are raised to be filled, lowered and subsequently carried round to be re-engaged by fingers 30¹ and carried be- 55

neath a pressure applying device 55 adapted to be oscillated from a shaft 59 to fold down the two end flaps of the upper end of the carton. The gear wheel 51a is only intermittent in its driving connection to the gear wheel 53 as likewise is the gear wheel 45¹ as regards its connection to the gear wheel 46¹. This is effected by splining the gear wheels 43¹ and 51 on to their shafts and forming a dog clutch connection between them and their associated wheels 45¹ and 51a respectively. A pair of transverse clutch actuating rods 67 and 68 are reciprocated axially from a lever 67a and 68a respectively operated from cams 67b and 68b actuated from a pair of shafts 69 and 70 geared as at 71 and driven via bevel gearing 72 and a shaft 73 from a common prime mover 74. Side frame members 93 support the various shafts.

The method of filling the cartons forms an important feature of the invention, and instead of filling the cartons as they are conveyed in the same direction of movement as the conveyor 6, i. e. rectilinearly as in existing practice, this rectilinear movement is converted into arcuate movement about the centre of the filling apparatus 31, and when each carton is filled it is deposited again on to the conveyor surface 16¹ and carried under the pasting device prior to sealing the carton. For this purpose the stationary centre post 23 (see Figs. 3 and 11) of the filling apparatus is a fork-like structure, between the limbs of which the upstanding prongs 30¹ of the conveyor are free to pass, the centre 24 of this centre post 23 forming a bearing about which 35 rotate a series of hoppers 25 carried by a frame 26 journaled about a shaft 28 upstanding from the forked post 23 and rotated intermittently by a gear wheel 29b (see Fig. 11) meshing with gear teeth 29, formed around the upper end of the 40 frame 26. The gear wheel 29b is carried by a vertical shaft 29c driven from a shaft 54 hereinafter referred to.

Each of said hoppers has depending from it a frame adapted to receive an empty carton and 45 also to slide upwardly relative to the hopper to fill the carton, after which the frame is lowered to release the carton on to the conveyor surface 16¹. Each hopper accommodates an interchangeable nozzle or delivery spout 25a, and by predetermining the dimensions of this nozzle or spout the rate of delivery of the material can be adjusted. For instance a commodity which would flow freely and quickly through a passage would require a small diameter delivery nozzle, whereas a commodity which is likely to clog or flow slowly would 55 require a large diameter delivery nozzle.

The said frame consists of two depending side arms 30 spaced apart approximately the same width as the space between the limbs of the 60 forked post 23 and having inwardly directed feet 30a upon which rests the base of a carton, these feet being spaced sufficiently to enable the prongs 30¹ of the conveyor 6 to pass freely between them. The frames composed of the arms 30 are brought 65 successively into alignment with the space in the post 23 so that the conveyor 6 may deliver an empty carton on to a frame at one side of the said post and convey a filled carton away from a frame at the other side of the post 23. This operation is shown in Fig. 1 as being effected by mounting four equidistantly spaced frames 30 about the post 23 and these are moved through 90 degrees intermittently, the interval between each such movement being occupied by a movement of the 70 conveyor 6 equal to the distance containing two

cartons 16, i. e. the distance between three prongs 30¹. By this means the conveyor 6 can bring an empty carton on to each of the two frames 30 which are in line with the conveyor, the other two frames being raised to the position to fill the cartons carried by them, from the appropriate hoppers. The next partial rotation of the hoppers will bring the two full cartons into alignment with the conveyor, and the two empty cartons to the filling position, the next operation 10 being a repetition of the movement of the conveyor 6 to carry the filled cartons from the appropriate frames 30 and replace them by empty cartons.

The cartons at their bases overhang the sides of 15 the conveyor surface 16¹ so that as the frames 30 are raised, their feet 30a engage and lift the empty cartons from the conveyor surface 16¹, or as the frames 30 are lowered they lower the bases 20 of the filled cartons on to the conveyor surface 20 for removal.

In Fig. 2 I have shown a hexagonal arrangement of the frames 30 about the centre post 23 and each frame is moved intermittently through 25 60 degrees, the periods between each such movement being occupied by an endwise movement of the conveyor equal to the distance between two successive prongs 30¹, the cartons being carried through a complete semi-circle from the supply side to the delivery side, the filling operation being 30 effected during this stage. By this means as a filled carton is taken from the appropriate frame 30 an empty one is placed on to the like frame on the diametrically opposite side of the filling apparatus.

The carton carrying frames 30 are each suspended from a pair of vertical side arms 33 secured at their upper ends to a yoke like bridge 34 provided with each hopper, the centre of each yoke 34 carrying a roller 35, these rollers being 40 adapted to travel along a fixed ring 36 having at diametrically opposite sides a cam shaped part 37 adapted to impart the desired raising and lowering action to the carton carriers 30. The ring 36 is carried by arms 38 depending from a fixed cover 45 plate 39 having a pair or other suitable number of funnels 32 disposed directly beneath the weighing and delivering apparatus 31 for guiding the commodity into the hoppers. When the empty cartons are raised they cover the lower 50 ends of the hoppers and to enable the air in the cartons displaced by the commodity delivered into the cartons from the hoppers to be released a number of vertical air passages 40 are provided outside each hopper, for instance as shown in 55 Figs. 4 and 11 by forming each hopper as a cylindrical chamber 41 fitted in a square section wall 42, the spaces between the chamber 41 and the wall 42 in the corners of the wall 42 forming the air passages 40 which are open top and bottom, their lower ends being brought into close alignment with the corners of the cartons during filling.

The upper ends of the hoppers will be aligned with the funnel shaped filling aperture 32 in the 65 cover plate 39 (see Fig. 11) when their lower ends are covered by cartons. This filling aperture 32 forms the means of transferring the weighed substance from the weighing and delivery apparatus to the hoppers. The cover plate 39 preferably has a depending web 43 located close to the inner side of the toothed ring 29 at the top of the frame 26, a suitable air tight sealing material 44 being located between the web 43 and the ring 29 so that the space within the cover plate 70 75

39 is sealed. A suction pipe can be connected to this said space to assist in a rapid release of the air from the cartons through the passages 40, this also expediting the charging of the cartons.

5 The post 23 can be replaceable to allow for different sizes of cartons to pass through it, and the feet 30a of the frames 30 can be adjustable towards and away from each other.

When the partly closed cartons are carried 10 from the filling stage they pass under a pasting roller 19 and are conveyed beneath mechanism to have their now upstanding flaps closed down.

15 The foregoing describes the various parts appropriate to the treatment of one line of cartons but the present invention is concerned with dealing with two or more rows of cartons and a corresponding number of filling apparatus 31, sets of formers 4, pressure members, pasting rollers and final closure and delivery mechanism.

20 By means of this arrangement of conveyors in one machine and transverse shafts and reciprocating bars each common to all of the conveyors and also a number of filling apparatus operated synchronously from a common source a machine 25 is provided which will deal with large quantities of cartons in a space smaller than would be possible with a number of separate machines.

I claim:

1. In apparatus for filling cartons, a conveyor 30 adapted to receive empty cartons at one end and to deliver them filled at the other end, a plurality of carriers rotating about an axis passing through and substantially at right angles to the carton carrying plane of travel of the said conveyor, means for automatically reciprocating said carriers in the direction of said axis and carton engaging members on said carriers adapted to lift and lower the cartons from and to the conveyor and during the lifting motion to move 40 the empty cartons into a filling stage.

2. In apparatus for filling cartons, a conveyor adapted to receive empty cartons at one end and to deliver them filled at the other end, a plurality of carriers rotating about an axis passing through and substantially at right angles to the carton carrying plane of travel of the said conveyor, means for automatically reciprocating said carriers in the direction of said axis and a pair of carton engaging abutments on said carriers 45 adapted to lift and lower the cartons from and to the conveyor and during the lifting motion to move the empty cartons into a filling stage, abutments at regularly spaced intervals projecting from said conveyor, the abutments on the conveyor being adapted to engage the empty cartons and push them between the pair of abutments on said carriers, said latter abutments being adapted to engage under the empty cartons and when the carriers are raised to lift the cartons from the conveyor and when the carriers are lowered to hold the filled cartons adjacent the conveyor whereby the said abutments on the conveyor engage the filled cartons and remove them from the said carriers.

3. Apparatus for filling cartons comprising a series of carriers mounted for rotation in a circular path about a vertical axis, filling apparatus above said carriers, an endless conveyor travelling in a direction substantially diametrically through the circular path of travel of the said carriers, means for reciprocating said carriers vertically, a pair of abutments on each of said carriers adapted to be located on opposite sides of the conveyor beneath the plane of travel of the bases of the empty cartons so as to engage

and lift the empty cartons from the conveyor to the filling apparatus and to subsequently lower the filled cartons on to the said conveyor.

4. Apparatus for filling cartons comprising a series of carriers mounted in diametrically opposite pairs about a common axis for rotation in a circular path, filling apparatus above said carriers, and an endless conveyor travelling in a direction substantially diametrically through the circular path of travel of the said carriers, abutments on said carriers for engaging and lifting empty cartons from the conveyor to the said filling apparatus and for transferring the filled cartons back to the said conveyor, upstanding abutments arranged at regularly spaced intervals along the conveyor against the leading sides of which abutments are adapted to be located empty cartons, means for reciprocating said carriers vertically relative to said conveyor, the arrangement being that each carton or package is filled 20 as it is moved by said reciprocation towards the filling apparatus above it, said filling operation taking place during translation of the appropriate carton or package from the conveyor through an arcuate path back to the conveyor. 25

5. Apparatus for filling cartons comprising a series of carriers mounted for rotation in a circular path about a vertical axis, filling apparatus above said carriers, an endless conveyor travelling in a direction substantially diametrically through the circular path of travel of the said carriers, means for reciprocating said carriers vertically, a pair of abutments on each of said carriers adapted to be located on opposite sides of the conveyor beneath the plane of travel of the bases of the empty cartons so as to engage and lift the empty cartons from the conveyor to the filling apparatus and to subsequently lower the filled cartons on to the said conveyor, a frame supporting the said carriers, hoppers carried by said frame and disposed singly above said carriers, said means for reciprocating the carriers comprising a projection associated with each carrier slidable on the frame and a track for engagement by said projection, said track containing a laterally displaced part for imparting a change of direction of movement to said projection to produce said sliding movement of each carrier relative to the hopper immediately above it.

6. In apparatus for filling cartons, a conveyor 50 adapted to receive empty cartons at one end and to deliver them filled at the other end, a plurality of carriers rotating about an axis passing through and substantially at right angles to the carton carrying plane of travel of the said conveyor, 55 means for automatically reciprocating said carriers in the direction of said axis and carton engaging members on said carriers adapted to lift and lower the cartons from and to the conveyor and during the lifting motion to move the empty 60 cartons into a filling stage, a frame supporting the said carriers, hoppers carried by said frame and disposed single above said carriers, said means for reciprocating the carriers comprising a circular track carried by said frame, lateral 65 projections carried by the carriers and travelling along said track, cam shaped parts in said track for imparting said sliding movement of each carrier relative to the hopper immediately above it.

7. In apparatus for filling cartons, a conveyor 70 adapted to receive empty cartons at one end and to deliver them filled at the other end, a plurality of carriers rotating about an axis passing through and substantially at right angles to the carton carrying plane of travel of the said conveyor, 75

filling apparatus above said carriers, means for automatically reciprocating said carriers in the direction of said axis and carton engaging members on said carriers adapted to lift and lower the cartons from and to the conveyor and during the lifting motion to move the empty cartons into a filling stage, the arrangement being that each carton or package is filled as it is moved towards the filling apparatus above it, said filling operation taking place during translation of the appropriate carton or package from the conveyor through an arcuate path back to the conveyor, a rotatable frame supporting the carriers, hoppers carried by said frame and disposed singly above said carriers, a circular track carried by said frame, lateral projections carried by the carriers and travelling along said track, cam shaped parts in said track for imparting said sliding movement of each carrier relative to the hopper immediately above it, a central vertical support for said frame and carriers, the carriers being arranged at a predetermined angle apart around said support, means for moving the frame intermittently through such angle in a uniform circular direction and for holding the conveyor stationary during such movement, and means for moving the conveyor during the stationary periods of said frame.

8. Apparatus for filling cartons comprising a series of carriers mounted for rotation in a circular path, filling apparatus with said carriers, an endless conveyor travelling in a direction substan-

tially diametrically through the circular path of travel of the said carriers, means on said carriers for lifting the empty cartons from the conveyor and for lowering the filled cartons back to the said conveyor, hoppers above the carriers and means for moving the carriers axially relative to the hoppers for carrying the cartons into filling stages, means for releasing air from the cartons during filling, projections on said conveyor adapted to engage the cartons delivered from a shaping and delivering means and to feed them to said carriers and also for engaging the filled cartons on the carriers so as to remove them from the carriers and deliver them to a closing stage.

9. In apparatus for filling cartons, a series of carriers, a conveyor, means for rotating the carriers in a circular path above the conveyor, a line of spaced abutments on the conveyor passing diametrically through the circular path of travel of the said carriers, means for reciprocating the carriers in the direction of their axis of rotation, abutments on said carriers, filling apparatus above the carriers, the abutments on the conveyor pushing the cartons successively above the abutments on the carriers when the carriers are in their lowest position whereby the cartons are raised with the carriers to the filling apparatus and carried through an arcuate path and subsequently lowered back on to the conveyor.

CARL WILHELM HARTMANN.
